UNITED STATES PATENT OFFICE.

HENRI DE THIERSANT, OF LONDON, ENGLAND.

ELECTRIC IGNITION DEVICE FOR GAS-BURNERS.

SPECIFICATION forming part of Letters Patent No. 740,062, dated September 29, 1903.

Application filed October 10, 1902. Serial No. 126,760. (No model.)

To all whom it may concern:

Be it known that I, HENRI DE THIERSANT, a citizen of the Republic of France, residing at 97 Cannon street, London, England, have invented new and useful Improvements in Electric Ignition Devices for Gas-Burners, of which the following is a specification.

This invention relates to improvements in electric ignition devices for gas-burners; and it consists in the novel features hereinafter described with reference to the accompanying drawings, which illustrate one form in which I have contemplated embodying my invention, and said invention is fully disclosed in the following description and claims.

To enable the invention to be fully understood, I will describe it by reference to the accompanying drawings, in which—

20 Figures 1 to 3 are front views of an incandescent gas-burner provided with a suitable form of my novel electric igniter, the said figures showing the gas-tap and sparking contacts in different positions, as hereinabove described. Fig. 4 is a side view thereof, the parts being in the same position as in Fig. 3; and Figs. 5, 6, and 7 are sectional plan views showing the gas-cock plug in the positions corresponding to those in Figs. 1, 2, and 3, respectively.

25 A is the main gas-burner, and a the plug of the gas-tap, the said plug being extended rearwardly through the body at the end opposite to that having the handle or thumb-piece b, the projecting end having a neck c, to one side of which is fixed a metal wire d, the end of which terminates in several coils e, inclosing the pilot-tube f. The rod d is secured in the neck c at a point such that when 30 the handle b of the plug is turned fully on the said point d' is at the top of its path.

Above the pilot-tube is placed a spring-contact g, which is fixed at h to an insulated portion of the device. This spring-contact is 35 connected by the wire i to one of the terminals of the source of electricity. The body of the device, and consequently the wire d, is connected to the other terminal of the source of electricity. The upper upper end 40 of the spring is advantageously curved toward the burner-tube, as shown in Fig. 4.

When the burner is turned off and the gas-

plug is in the position illustrated in Fig. 1, the upper bent end d² of the wire d is above the upper end of the pilot-tube f. If now 55 the tap b be manipulated so as to first open the passage conveying gas to the pilot-tube f, the rod d is moved by the plug and rises at the same time, sliding up the pilot-tube f. The upper bent end d² of the rod then comes 60 into contact with the spring g, slides up the same, and springs off its end, thereby forming a disruptive spark, which ignites the gas issuing from the pilot-tube f. This flame will be communicated to the gas issuing from 65 the main burner, which will be ignited at the moment when the parts are in the position indicated in Fig. 3, and the passage of gas to the pilot-tube f is cut off. By continuing to turn the cock-plug the flame is 70 regulated without igniting the pilot-flame. It will be seen by reference to Figs. 1, 2, and 3 that as the plug is turned the movement of the eccentric connection d' of the movable contact will cause the upper portion of said 75 movable contact to turn laterally with respect to and upon the pilot-tube. Therefore in the further movement of the plug beyond the position indicated in Fig. 3 for the purpose of regulating the flame of the main 80 burner A the movable contact will be drawn downward, thereby swinging it still farther around the pilot-tube and out of operative relation to the stationary contact g. Therefore the two contacts will not be brought together when the plug is being moved through this portion of its half-circle of movement, and the flame of the main burner A can therefore be accurately regulated without danger of short-circuiting the battery-current. On 85 turning back the plug in the opposite direction the tap is completely turned off. It will be seen that with this arrangement the movable device producing the spark moves parallel with the main burner in a vertical plane. 90 The result of this is that the device can be applied to burners with a gallery at some distance from the cock. It will only be necessary to increase the height of the pilot-tube and to elongate the wire d-d'-d². This elongation will in no way modify the reciprocal 95 relations of the parts, and the spark will always be produced at the same moment without the gallery interfering with the operation.

Another advantage consists in the fact that the spark is produced exactly at the point desired to ignite the gas issuing from the pilot-tube, since this spark is always produced 5 at the same point exactly above the pilot-tube.

Having now particularly described and ascertained the nature of my said invention and in what manner the same is to be performed, 10 I declare that what I claim is—

1. The combination of a gas-burner, a pilot-tube for lighting same, a fixed contact having a part adjacent to the ignition end of the pilot-tube, a movable contact constructed to 15 simultaneously slide vertically and oscillate upon the pilot-tube and having a part for engaging the fixed contact, a gas-tap for controlling the said burner and pilot tube and a

connection between said gas-tap and the movable contact having an eccentric connection 20 with said tap, substantially as described.

2. The combination of a gas-burner, a pilot-tube for lighting same, a fixed contact having a part adjacent to the ignition end of the pilot-tube, a gas - tap for controlling said 25 burner and pilot tube, and a movable contact having a part coiled around, and adapted to slide and oscillate upon the pilot-tube, a part for engaging the fixed contact and a part connected eccentrically to said tap, substantially 30 as described.

HENRI DE THIERSANT.
